DESIGN FOR A CABINET FOR A PHONO- GRAPH OR THE LIKE

Henry T. Roberts, Chicago, Ill., assignor to J. P.
Seeburg Corporation, Chicago, Ill., a corporation of Illinois

Application June 20, 1938, Serial No. 77,961

Term of patent 7 years

To all whom it may concern:

Be it known that I, Henry T. Roberts, a citizen of the United States and a resident of Chicago, in the county of Cook and State of Illinois, have invented a new, original, and ornamental Design for a Cabinet for a Phonograph or the like, of which the following is a specification, reference being had to the accompanying drawing, forming part thereof.

Figure 1 is a perspective view of a cabinet for a phonograph showing my new design.

Figure 2 is a side elevational view; and Figure 3 is a top plan view.

I claim:

The ornamental design for a cabinet for a phonograph or the like, substantially as shown.

HENRY T. ROBERTS.
